(57) **CLAIM**

I claim the ornamental design for a mobile phone with digital camera, as shown and described.

DESCRIPTION

FIG. 1 is a front, top, and left side perspective view of my new design for a mobile phone with digital camera;
 FIG. 2 is a rear perspective view of our new design;
 FIG. 3 is a perspective view of our new design with the keypad slid shut;
 FIG. 4 is a perspective view of our new design with the keypad slid shut and the antenna up;
 FIG. 5 is a front elevation view thereof;
 FIG. 6 is a rear elevation view thereof;
 FIG. 7 is a left side elevation view thereof;
 FIG. 8 is a right side elevation view thereof;
 FIG. 9 is a top plan view thereof; and,
 FIG. 10 is a bottom plan view thereof.
